SOAP DISPENSING SHAMPOO BRUSH

Flora H. Ellinger, Chicago, Ill.

Application August 8, 1946, Serial No. 689,127

5 Claims. (Cl. 15—131)

1

My present invention relates generally to improvements in the art of conditioning hair and relates more particularly to improvements in the construction and operation of shampoo soap dispensers and brush units especially adapted for use in washing hair.

A primary object of the present invention is to provide a new and useful improved shampoo brush which is simple and compact in construction and highly efficient in use.

A more specific object of this invention is to provide an improved combined hair brush and soap dispenser with which liquid shampoo soap may be readily utilized for effectively cleansing the hair.

Another specific object of my invention is to provide an improved shampoo brush wherein a liquid soap may be conducted to the area being scrubbed in a convenient manner at the will of the user.

Another specific object of the invention is to provide an improved sanitary shampoo brush for hair which may be readily filled with a supply of liquid soap or the like adapted to be conducted in desired quantities to the scrubbing or washing area.

Another specific object of the present invention is to provide an improved hair shampoo brush embodying a soap dispensing unit which is simple in construction and wherein the valve means controlling the supply of soap dispensed to the scrubbing area is automatically closed.

An additional specific object of this invention is to provide an improved new and useful hair conditioning assemblage which is especially adapted for shampooing and which may be conveniently and quickly manufactured of sheet metal, plastic or the like.

A further specific object of my invention is to provide an improved portable hair washing or shampooing device which may be used by a novice to effectively cleanse hair and which may nevertheless be readily merchandized at relatively low cost.

Still another specific object of my present invention is to provide an improved sanitary and conveniently manipulatable shampoo brush and soap dispenser unit which may be easily manipulated to produce the desired amount of lather during use.

These and other specific objects and advantages of the present invention will be apparent from the following detailed description.

A clear conception of the several features constituting my present improvement and of the

2

mode of constructing and of utilizing shampoo brushes built in accordance with my invention may be had by referring to the drawing accompanying and forming a part of this specification wherein like reference characters designate the same or similar parts in the several views.

Fig. 1 is a top view of an improved shampoo brush and soap dispenser assemblage built in accordance with my invention and with the cover 10 for the soap chamber removed; and

Fig. 2 is a section through the brush taken along the line 2—2 of Fig. 1.

While the invention has been shown and described herein as being specifically applied to a brush and liquid soap dispensing assemblage especially adapted for shampooing or otherwise conditioning hair it is not my desire or intention to thereby unnecessarily restrict the scope or utility of the improvement.

20 Referring to the drawing, the improved shampoo brush assemblage comprises, in general, a substantially flat brush plate 5 having bristles 6 projecting from the face thereof and having an integral stub shaft 7 projecting centrally from the back side thereof, the brush plate 5 being provided with an aperture 8 shown as being a radial slot; a gripping handle 9 secured to or formed integral with the brush plate 5 and projecting laterally therefrom, the handle 9 being provided with

25 an upward projection or stop 10; an annular casing 11 having an inner wall 12 formed to embrace the stub shaft 7, and an outer wall 13 of sufficient height to extend some distance above the stub shaft 7, the casing 11 forming a housing 30 for liquid soap and having one or more apertures or perforations 14 in the base thereof which are adapted to register with the aperture 8 in the plate 5 upon rotation of the casing; a leaf spring 35 15 held at one end within a slot 16 in the upper end of the stub shaft 7 by a pin 17 and extending laterally from the shaft 7 toward the inner surface of the outer wall 13 of the casing 11, and cooperating with inwardly extending lugs 18, 18' formed on the outer casing wall 13; a trigger 19 40 formed on the outer surface of the casing outer wall 13 and adapted to cooperate with the stop 10 on the handle 9 during use, as will hereinafter be more fully described; and a cover 20 for the casing 11.

45 The brush plate 5 may be formed of any suitable material such as metal, plastic or rubber and the bristles 6 may be secured to the plate 5 in any suitable well-known manner. The handle 9 may be attached to the plate 5, or it may be formed integral therewith and the trigger stop 10 may

50

likewise be formed as an integral part of the handle 9. The plate 5 is preferably dished as at 21 to form a bearing for the annular casing 11 adapted to house a supply of liquid soap as illustrated, and the cover 20 may be screw threaded to the outer wall 13 of the casing or it may be merely formed with a relatively tight fit. Obviously, any desired number of apertures 8 in the plate 5 and any desired number of perforations 14 in the base of the casing 11 adapted for registry with the apertures 8 may be provided. Care must be taken, however, to form the trigger 19 on the casing wall and the trigger stop 10 on the handle so that when the trigger is positioned against the stop, the perforations 14 will register with the aperture 8 to permit liquid soap from the casing or housing 11 to pass to the area being scrubbed by the bristles 6. For convenience in removing the cover to reveal the casing 11 the cover 20 may be provided with a suitable gripping knob 22 as shown.

The various parts of the assemblage may be readily manufactured and assembled by merely placing the casing in place on the stub shaft, thereafter attaching the leaf spring 15 by means of the pin 17 to the stub shaft 7, and finally filling the casing with liquid soap and placing the cover 20 thereon.

During normal use of the improved shampoo assemblage the user may readily supply the desired amount of shampoo soap to the hair by moving the trigger 19 with a thumb against the stop 10 on the handle 9, thus registering the perforations 14 in the base of the casing 11 with the slot 8 in the plate 5. After the desired amount of soap has been permitted to pass through the perforations 14 and slot 8 to the area being washed or shampooed, the user merely need release the pressure on the trigger 19 and the casing will be automatically rotated by means of the leaf spring 15 coacting with the lug 18 to a position wherein the perforations 14 of the casing are out of registry with the slot 8, thus closing the soap supply passage. It should be noted that in addition to functioning to automatically return the casing to a position such as will close the ports 14 and 8, the leaf spring 15 also cooperates with the inner wall 12 of the casing to prevent removal of the casing 11 from the shaft 7; and the lug 18 acts as a stop to prevent reverse over-movement of the casing 11 in an obvious manner.

From the foregoing detailed description it is apparent that my present invention provides an improved shampoo brush assemblage which is simple and durable in construction and which is moreover highly efficient in actual use. The improved assemblage is composed of relatively few parts which may be readily and quickly manufactured of available material either stamped or molded. In addition to its utility as a brush and soap dispensing unit the improved assemblage is compact and neat in appearance and is sanitary and free of protruding parts, which are apt to catch dirt and the like. The supply of soap to the scrubbing zone may be controlled in a simple and efficient manner and the means for positioning the casing so as to close the ports to the scrubbing zone functions in an entirely automatic manner. Obviously, by virtue of the simplicity of the assemblage, relatively little wear is given the various parts and all of the parts may be readily replaced at low cost when and if necessary.

While the improved shampoo brush and soap dispensing assemblage has been specifically shown

and described herein as having the limit stop for the trigger formed integral with and on the upper portion of the handle, and with a pair of perforations in the casing base adapted for registry with a single slot in the brush plate and with the leaf spring 15 secured to the stub shaft 7 in a particular manner, the device may obviously be modified with the trigger stop located in a different manner with more or less perforations 14 and slots 8 and with the leaf spring secured to the stub shaft 7 in some other manner without departing from the spirit of the invention. The assemblage may obviously also be utilized for other than hair conditioning purposes.

It should therefore be understood that it is not desired to limit this invention to the exact details of construction or to the precise mode of use herein shown and described, for various modifications within the scope of the appended claims may occur to persons skilled in the art to which this invention pertains.

I claim:

1. A shampoo brush assemblage comprising, a brush plate having bristles projecting from the face thereof and having a shaft projecting from the back thereof, said brush plate having an aperture therethrough, a liquid soap housing mounted for rotation about said shaft and having an aperture in the base thereof adapted for

25 registry with the aperture in said plate, said housing having its bottom contiguous with and slideable upon the top of said brush plate, and means for rotating said soap housing a predetermined distance about said shaft to cause the aperture in said housing to register with the aperture in said plate.

2. A shampoo brush assemblage comprising, a brush plate having bristles projecting from the face thereof and having a shaft projecting from the back thereof, said brush plate having an aperture therethrough, an annular casing forming a liquid soap housing mounted for rotation about said shaft, said casing having its bottom contiguous with the top of said brush plate and having an aperture therein adapted for registry with the aperture in said brush plate, means associated with said casing for rotating the same a predetermined distance about said shaft to cause the aperture in said casing to register with the aperture in said plate, and means cooperable with said shaft and with said casing for automatically returning said casing to a position in which the aperture in said casing is out of registry with the aperture in said plate.

40 3. A shampoo brush assemblage comprising, a brush plate having bristles projecting from the face thereof and having a stationary stub shaft projecting from the back thereof, said brush plate having an aperture therethrough, an annular casing having inner and outer walls forming a liquid soap housing mounted for rotation upon said shaft with the inner wall of said casing surrounding said shaft, said casing having its bottom contiguous with the top of said brush plate and having an aperture therein adapted for registry with the aperture in said brush plate, means associated with said casing for rotating the same a predetermined distance about said shaft to cause the aperture in said casing to register with the aperture in said plate, and means cooperable with said shaft and with said casing for automatically returning said casing to a position in which the aperture in said casing is out of registry with the aperture in said plate.

45 5. A shampoo brush assemblage comprising, a brush plate having bristles projecting from the face thereof and having a stationary stub shaft projecting from the back thereof, said brush plate having an aperture therethrough, an annular casing having inner and outer walls forming a liquid soap housing mounted for rotation upon said shaft with the inner wall of said casing surrounding said shaft, said casing having its bottom contiguous with the top of said brush plate and having an aperture therein adapted for registry with the aperture in said brush plate, means associated with said casing for rotating the same a predetermined distance about said shaft to cause the aperture in said casing to register with the aperture in said plate, and means cooperable with said shaft and with said casing for automatically returning said casing to a position in which the aperture in said

60 6. A shampoo brush assemblage comprising, a brush plate having bristles projecting from the face thereof and having a stationary stub shaft projecting from the back thereof, said brush plate having an aperture therethrough, an annular casing having inner and outer walls forming a liquid soap housing mounted for rotation upon said shaft with the inner wall of said casing surrounding said shaft, said casing having its bottom contiguous with the top of said brush plate and having an aperture therein adapted for registry with the aperture in said brush plate, means associated with said casing for rotating the same a predetermined distance about said shaft to cause the aperture in said casing to register with the aperture in said plate, and means cooperable with said shaft and with said casing for maintaining said casing in position on said shaft and for automatically returning said casing to a position in which the aperture in said

casing is out of registry to the aperture in said plate.

4. A shampoo brush assemblage comprising, a brush plate having bristles projecting from the face thereof and having a stationary stub shaft projecting from the back thereof, said brush plate having an aperture therethrough, an annular casing having inner and outer walls forming a liquid soap housing mounted for rotation about said shaft with said inner wall surrounding said shaft, said casing having its bottom contiguous with the top of said brush plate and having an aperture therein adapted for registry with the aperture in said brush plate, an inwardly directed lug formed on the outer wall of said casing, means associated with said casing for rotating the same a predetermined distance about said shaft to cause the aperture in said casing to register with the aperture in said plate, and means carried by said shaft and cooperable with the inner wall of said casing for maintaining said casing in position on said shaft, said last mentioned means being also cooperable with the lug on the outer casing wall to automatically return said casing to a position in which the aperture in said casing is out of register with the aperture in said plate.

5. A shampoo brush assemblage comprising, a brush plate having bristles projecting from the face thereof and having a stationary stub shaft projecting from the back thereof, said brush plate having an aperture therethrough, an annular casing having inner and outer walls forming a liquid soap housing mounted for rotation about

said shaft with the inner casing wall surrounding said shaft, said casing having its bottom contiguous with the top of said brush plate and having an aperture therein adapted for registry with the aperture in said brush plate, an inwardly directed lug formed on the outer casing wall, means associated with said casing for rotating the same a predetermined distance about said shaft to cause the aperture in said casing to register with the aperture in said plate, and a leaf spring secured to said shaft and extending laterally therefrom about the inner casing wall and adapted to coact with the lug of the outer wall of said casing to maintain said casing in position on said shaft and to automatically return said casing to a position in which the aperture in said casing is out of registry with the aperture in said plate.
